SNAP SWITCH

Walter Von Stoeser, Lake Villa, Ill., assignor, by
mesne assignments, to Moco Products, Inc.,
Chicago, Ill., a corporation of Illinois

Application May 9, 1950; Serial No. 160,939

3 Claims. (Cl. 200—67).

1

This invention relates to improvements in snap-action switches of the type commonly known as stack or leaf-spring switches, such as exemplified in my prior U. S. Patent No. 2,500,476 (class 200/67).

Such switches are characterized mainly by the provision of a number of thin elongated contacts, which are arranged one above another, each with one end held in a common stack of insulation and spacing wafers, at least one of the contacts being of spring metal for flexing into and out of contacting engagement with other contact blades in the stack.

In the snap-action variety of this switch, some form of over-center spring mechanism is usually included near the free or unattached ends of the switch blades to snap one of the blades to a certain position when another one of the blades is flexed a certain amount, the over-center spring arrangements being contrived in a number of different forms of construction to achieve various operating and manufacturing desiderata.

The present improvements pertain especially to details of the snap-action mechanism which prolong the operating life of the switch; afford very good contact pressures on both sides of the throw, stabilize the operation of the over-center spring, and permit various spacings of the stationary contacts without any attention to the spring tension or angular attitude.

Other objects and aspects of utility in the improved switch structure pertain to details of the construction and operation of the embodiment described hereinafter in view of the annexed drawing, in which:

Fig. 1 is a side elevation of the switch;

Fig. 2 is a top plan view of the same;

Fig. 3 is an enlarged, fragmentary section taken along lines 3—3 of Fig. 2;

Fig. 4 is a perspective assembly detail of the improved over-center spring means.

In Fig. 1 is shown a simple stack switch consisting of a pair of opposite, rigid, stationary contacts 10 and 11, secured in spaced relation between insulating wafers in the stack 12, which is held tightly assembly by bolts 13.

Also mounted in the stack is a flexible or movable contactor 14 (Fig. 3, also), which is intended to be moved back and forth between the two stationary contacts 10 and 11.

Snap-action of the movable contact is effected through the agency of an operator arm 15, which is of spring metal, also, but which is longer than all of the other contact elements, but like the others, has one of its ends fixed in the stack 12.

Between its end regions, the operator arm 15 has a longitudinally extensive cut-out area 16,

2

which is large enough to permit the movable contactor 14 to pass up and down in directions opposite to the back and forth motions of the operator arm 15.

5 The snap-action means is shown to advantage in Fig. 3 and includes a peculiarly shaped bow spring 18 (see Fig. 4) having a transverse arm 19 at one side of the bow, and an offset 20 at the other side of the bow.

10 The bow spring 18 is attached to the operator arm adjacent the tongue 14A and free end of blade 14 by means of a rivet 21, and preferably the offset 20 is provided with a small positioning lug 22, which fits into a punched opening 23 in the operator arm.

15 The lateral arm 19 of the especially shaped snap spring affords two fingers 19A and 19B, which are caused to rest (Fig. 2) on the opposite sides of the operator arm bordering the cut-out; the tension of the bow-spring and the fixation of the rivet means 21 being intended to bias the spring so that said fingers 19A and 19B locate the spring in a predetermined attitude and condition of slight tension.

20 The aforesaid biased locating of the bow spring has as one of its purposes the registration of an actuator slot 24 (Figs. 3 and 4) in the bow spring in a desired position approximately within the plane of the operator arm, or in other terms, practically inside the cut-out area of said arm, the importance of which will become more apparent hereinafter.

25 The snap-action mechanism is completed by the provision of a throw member or actuator 26, having an endwise tongue 25 fitting into the spring slot 24, and also having an endwise offset 27 in which is a slot 28 receiving the endwise tongue 14A of the contactor blade. The actuator slot 28 is below the registered or aligned position of the spring slot 24 in the normal condition of the switch (i.e. as in Fig. 1).

30 Fig. 3 shows the switch in operated condition, from which it will be observed that the bow spring 18 cannot be displaced downwardly from its registered position as determined by the aligning means or fingers 19A, 19B, notwithstanding that the thrust of the actuator 26 in this attitude would tend to displace the bow spring downwardly were it not for the aligning fingers 19A, 19B.

35 While it is possible, by application of excessive force, to displace the operator arm 15 downwardly beyond the normally intended and proper range shown in Fig. 3, the especial positioning and limiting of displacement of spring 18 permits a considerable overtravel of arm 15 in the operating direction, without any improper opening of con-

tacts 10—14, and without any practical decrease of contact pressure.

In the absence of the positioning and limiting means 19A, 19B, the resultant displacement of the spring 18 under the foregoing conditions of over-travel would be at once apparent in an opening of the switch at a time when it is supposed to be closed, or an objectionable relaxation of the contact pressure.

The contact pressure in the normal condition of the switch is mainly dependent upon the resilience and bias of the movable blade 14. In the present construction, this bias can be quite strong, giving maximum normal contact pressure, without making the switch sluggish or unreliable in snap-action, owing to the maintainance of the spring bow always in the same normal position as determined by the positioning means 19A, 19B. There is a minute movement of the parts 19A, 19B on the sides of the operating arm 15, but no objectionable wear results from this.

The contact spacing or clearance for a given switch size can be altered through a range of many thousandths of an inch without the necessity of adjustment or change in the over-center snap-action, the device in these respects operating as satisfactorily at a contact clearance of ten-1,000th inch as at sixty-two 1,000th inch in the proportionate size illustrated.

The spring bow and associated over-center parts have an exceptionally long operating life even under extreme conditions inclusive of continuous, very rapid operation.

In prior types of snap switch of this class the spring bow is appreciably displaced at some phase of the overcenter movement, and this changes the relative positions of the toggle, rocker, or other over-center actuator, and the spring, particularly at the point of engagement of these parts. But in the present improvement, it will be noted by comparison of Figs. 1 and 3, that the juncture points at 24—25 are not appreciably displaced from the plane of the operating blade 15 in the operated and normal positions of the moving blade 14 and operating blade 15; and that it is the actuator or throw-element 26 which changes angularly with respect to the bow spring.

Since the spring 18 cannot move downwardly and the juncture 24—25 is at the fulcrum of the actuator 26, the latter at its tongue 25 in slot 24 likewise moves almost imperceptably, so that the displacement of the actuator 26 is translated mainly into a useful compressive thrust against spring 18 at the point of engagement 24—25 therewith, and the over-center action is smooth and reliably uniform up to and beyond dead center, whereas in the types of over-center mechanism in which the spring can move in an arc, a considerable change in both the angle and magnitude of thrust occurs rapidly in the region of dead center, and not only results in useless lost motion, but such devices often require critical adjustment or production tolerances, and are likely to be unreliable if not properly operated or if they are exposed to any rough treatment or abuse.

Another advantage of the improved spring means resides in the fact that the operating arm need not be formed, which is to say that it may be used just as it comes from the die without any crimping, bending, or other adjustment, as is the case with certain prior spring devices of this class.

In the absence of the disclosed locating means to prevent downward movement of the spring 18, and to maintain the bow under tension, this

class of snap-switch will frequently hang up in operated condition; that is to say, it will become jammed in operated condition—especially if there is any appreciable over-travel permitted the operating arm; whereas, the improved over-center spring structure revealed herein eliminates such operating failures in both directions, it being noted that over-travel in the releasing direction tends to compress the spring increasingly and prevent its ever moving into a position where it could jam.

I claim:

1. A snap-acting stack switch comprising: a moving blade, an operating blade having a cut-out in which the free end of the moving blade can move, stop contacts flanking the moving blade to limit the throw thereof, a bow spring having one end offset and fastened at a margin of the cut-out in the operating blade remote from the free end of the moving blade, said bow spring having a lateral arm at its opposite end and bearing upon opposite margins of said cut-out to align the spring in the cut-cut against displacement therefrom in one direction, at least, and an actuator member having tongue and slot engagement with said free end of the moving blade and with said bow spring at a point close to said lateral arm thereof and which is substantially in the plane of said operating blade.

2. In a snap-action switch, a movable contactor blade held at one end, means flanking the free end of the contactor blade to limit its movements, an operating blade similarly held at one end in parallel assembly with the contactor blade and having an opening through which said free end of the contactor blade may pass, a bow spring having an end region attached to said operating blade in said opening and having means at an opposite end region engaging opposite sides of said opening in the operating blade to dispose said spring in a certain position in said opening and prevent movement of the spring in a certain direction out of said opening, and a throw-actuator having relatively offset means at its opposite ends respectively loosely engaging said free end of the contactor blade and said opposite end region of the bow spring to throw the contactor blade responsive to movements of the operating blade.

3. In a snap-action stack-switch of the class described and having an operating arm with a cut-out, and a moving contact blade with a free end portion working in said cut-out, improvements in a snap-action mechanism comprising: the following, to wit: a bow spring fastened on said operating arm in said cut-out adjacent the free end of said operating arm, and aligning means on said bow spring for engagement with marginal portions of said cut-out to dispose said spring in a predetermined condition of alignment, and a throw lever operatively connected with said free end of the moving contact blade and having a movable operating connection with said bow spring at a point on the latter which is substantially within the plane of said operating blade.
